UNITED STATES PATENT OFFICE

154,666

DESIGN FOR A GAME BOARD

Jay C. Davis, Groton, Conn.

Application October 17, 1947, Serial No. 141,990

Term of patent 3½ years

(Cl. D34—5)

To all whom it may concern:

Be it known that I, Jay C. Davis, a citizen of the United States, residing at Groton, in the county of New London and State of Connecticut, have invented a new, original, and ornamental Design for a Game Board, of which the following is a specification, reference being had to the accompanying drawing, forming part thereof.

I claim:

The ornamental design for a game board, as shown.

JAY C. DAVIS.
